BUNKER AND AIR CIRCULATING FAN ASSEMBLY FOR REFRIGERATOR CARS

Paul K. Beemer, Inglewood, Calif., assignor to
Preco Incorporated, Los Angeles, Calif., a corporation of California

Application August 5, 1947, Serial No. 766,399

3 Claims. (Cl. 62—24)

1

This invention has reference to the structure and design of refrigerator cars equipped with forced air circulation; and the purpose of the invention is to combine the structure and design of the ice bunker and the air circulating fan in such manner that the fan housing forms a part of, and the supporting structure for the bunker bulkhead, either movable or stationary, and in such manner that the bulkhead overlies and protects the fan housing from physical injury.

Other objects and corresponding effects and results of the invention will be explained along with a detailed explanation of preferred structures and designs, shown in the accompanying drawings in which:

Fig. 1 is a fragmentary longitudinal vertical section showing the present preferred design including a movable or convertible bulkhead;

Fig. 2 is a transverse section at somewhat reduced scale, taken as indicated by line 2—2 on Fig. 1, and also showing a typical mechanism for driving the fan, said mechanism not being shown in Fig. 1;

Fig. 3 is a fragmentary plan section taken as indicated by line 3—3 on Fig. 1 and with parts broken away for illustrative purposes, and

Fig. 4 is a section similar to that of Fig. 1 but showing a stationary bulkhead.

In the drawings various parts of a car structure are shown merely in diagrammatic form. The parts so illustrated and referred to herein are to be taken as typical of any car structure. In Fig. 1 a part of the car floor structure is indicated at 10, and in Fig. 2 the whole thickness of a typical car floor structure and framing is indicated diagrammatically at 10a. The upper layer of that whole floor structure, the part indicated 10b in Fig. 1, forms what is usually referred to as the floor of the lading compartment of the car. Over that floor is spaced the raised lading floor, usually comprised of transverse slats 11, as shown more or less diagrammatically in Figs. 1 and 3. The end wall of the lading compartment is formed by the bulkhead which stands permanently, or when in use as such, in the position indicated at B in Figs. 1 and 3, dividing the lading compartment from the ice bunker which is formed between the bulkhead at B and the end wall structure 12 of the car. That end wall structure is again shown merely diagrammatically and typically in Fig. 1. The ice bunker may typically be provided with an ice grate, either permanently at the level of lading floor 11, or movable to that level. Such an ice grate at such a level is indicated

generally at 13 and, insofar as the present invention is concerned, may be of any type or structure.

In the present preferred design the forward edge of ice grate 13 is supported on brackets 15. These brackets and the forward edge of the ice grate, are spaced from the adjacent edge of lading floor 11 by a distance which is approximately just sufficient to accommodate fan housing 16, which in general may be described as a metallic housing of approximately square section as seen in Fig. 1 and extending in length transversely across approximately full width of the car floor. The base plate 17 of the fan housing, in the preferred design here shown, rests directly on top of the car floor sheathing 18 which has its rear edge extending into and bent downwardly over the forward wall 14a of the drip pan 14. The metal forming the drip pan is extended forwardly in the form of an apron 14b under the extended part of floor sheathing 18 which lies directly under base plate 17 of the fan housing. The whole fan housing is secured to the car floor structure typically by bolts or lag screws, such as shown at 19.

Fan housing 16, as will appear, is a unitary structure of considerable inherent stiffness including the base plate, a vertical wall and a cover plate 20. In the preferred design shown in Fig. 1, the movable bulkhead rests directly on cover plate 20 when the bulkhead is in its position of use. The upper surface of cover plate 20 is flush with the upper floor surface of lading floor 11 and with the upper surface of ice grate 13. Bulkhead B, as here shown merely diagrammatically comprises a wall body structure 21 with an interior facing 22 and an external facing 23. It extends substantially across the full width of the car, either having a slight clearance of the car side walls at its vertical edges, or having suitable contact strips 30 as shown in Fig. 3. In Fig. 3 the bulkhead is indicated merely in block section, fragmentarily, for clarity of illustration. On its bottom edge surface the bulkhead is shown as equipped with a seating plate 24, integrated with the bulkhead wall structure 21, and having at its forward edge a down-turned rib 25. Seating plate 24, and its rib 25, extend over the whole length of the bottom face of the bulkhead (from side to side of the car). The rib projects downwardly into a seating channel 26 which is formed in a forwardly extended portion of top plate 20 of the fan housing. This

seating channel also extends approximately the full width of the car and the full width dimension of the bulkhead, extending as it does throughout the whole length of cover plate 20. This extended channel formation is supported on the fan housing by suitable supporting brackets 27. The channel formation lies forward of the outer, forward wall 43 of the fan housing, and below the level of the cover plate, and lading floor. In this position it does not obstruct the lading floor surface, and allows the seating plate 24 to rest directly on the cover plate over the vertical wall 43 when rib 25 is in the channel. Plate 24 with its rib 25 being integrated with and lying directly under the structural wall part 21 of the bulkhead, the latter is given good support both vertically and horizontally against load thrusts.

The bulkhead B as shown in Figs. 1 to 3 is one of the type which, to be moved from position B and thus to make the ice bunker space available for lading, is first moved upwardly from its position shown at B far enough to clear rib 25 from channel 26. It may then be moved to any other desired position, for instance against the end wall. It is then moved rearwardly to the plane of the position shown at B₁ against the end wall, and dropped down to a position where its securing ribs 25 is received in a channel formation 26a formed in the ice grate structure. With the bulkhead in that position, cover plate 20 becomes an effective part of the lading floor, as does also the ice grate. The type of lifting and moving mechanism by which the bulkhead is moved is immaterial to the present invention; as is also the particular internal structure of the bulkhead wall itself. The upper end of the bulkhead may be secured in positions B and B₁ by laterally projecting lugs which drop down into fixed sockets when rib 25 drops down into channel 26 or 26a. Suitable bulkhead structures and suitable means for lifting, moving and securing it are shown in the copending application of Herbert Wieden, et al., Ser. No. 685,510, filed July 22, 1946.

The over-all thickness of bulkhead B may have any desired relation to the width dimension of fan housing 16. As here shown, its over-all thickness is approximately the same as that width dimension, but the location of securing rib 25 in cover plate channel 26 forward of the body of the fan housing locates the rear or interior face 22 of the bulkhead some distance forward of the rear edge of cover plate 20. The rear part of the cover plate, and of the fan housing body, thus extend rearwardly of the bulkhead inner face. The rear part of the cover plate thus in effect becomes a part of the ice supporting structure in the bunker. And to prevent melt water from flowing into the interior of the fan housing (down the inner face of fan housing rear wall 42), the rear edge of cover plate 20 is extended and bent downwardly in a protective overhang as shown at 20a. This rear wall 42 of the fan housing is, in effect, a lower part of the front wall of the ice bunker.

Fig. 4 shows a structure which is similar in all respects to that shown in Fig. 1 except to show a stationary bulkhead B₂ mounted permanently in a position on fan housing 16. Bulkhead B₂ is shown as made up of a wall structure 21a and a facing 23a. The structural portion 21a of the bulkhead wall includes a flanged inverted channel member 21b at its base; and the flanges of this channel member are permanently secured to

cover plate 20b in any suitable manner, as by bolts 21c. These flanges are preferably wide enough that their edges lie over the vertical walls 42 and 43 of the fan housing.

5 The thickness of the bulkhead wall structure 21a is here less than the width dimension of housing 16 and cover plate 20b; and with the wall structure centered above the fan housing, the bulkhead inner facing 22a is forward of the 10 rear edge of cover plate 20b. The rear portion of the cover plate consequently becomes in effect a part of the ice supporting structure in the ice bunker, the same as in Fig. 1; and the rear edge is provided with the same downturned overhang 15 20a to shed melt water exteriorly of the rear housing wall 42. The forward edge of the cover plate, in this form, is also provided with a similar down-turned overhang 20c.

Other than described above, the arrangement 20 in Fig. 4 is essentially the same as in Fig. 1 and the same numerals are applied to corresponding parts. The ice grate and the cover plate of the fan housing are shown here as being at the same level as in Fig. 1. However, in this arrangement 25 where a fixed bulkhead is used, their level is not necessarily restricted to the level of the lading floor. The fan structure and housing can, if desired, be larger in cross section and of greater height; and then, or in any case, the ice grate can 30 be at a higher level.

In both the arrangements of Figs. 1 and 4 the fan housing structure may be and is shown as the same; shown in essentials in Figs. 2 and 3. Any suitable drive mechanism may be used for 35 the fan, insofar as the present invention is concerned. Fig. 2 shows a typical drive mechanism. The fan housing structure, the fan structure, and the driving mechanism, in and of themselves are not subject-matters of the present invention. The fan structures and arrangements here shown are the subject-matters of the patents to William E. Van Dorn No. 2,214,210 dated September 10, 1940, and No. 2,349,315 dated May 23, 1944. The fan housing structure is also the 40 subject-matter of application Ser. No. 614,220 filed September 4, 1945, by Frederick C. Lindvall, et al. now Patent No. 2,442,420, issue date June 1, 1948. And the particular driving mechanism here illustrated as typical is the subject-matter 45 of the patent of William E. Van Dorn, No. 2,413,158, dated December 24, 1946.

The fan housing structure is in essence composed of the bottom plate 17, of the top plate 20 and of a vertical wall structure which, as shown 50 best in Fig. 3, is of zig-zag formation. In essence, this vertical wall structure may be thought of as being composed of a long strip of heavy sheet metal, of a width equal to the vertical wall height, bent into the zig-zag form to provide both the longitudinal and cross wall elements of the housing; although in practice this structure is made up of several unitary pieces which are welded into a unitary whole. The structure, however 55 composed, is bent so as to form two transverse end walls 40 and several intermediate cross walls 41; with intervening front and rear wall portions 43 and 42 which extend between alternate pairs of the end and intermediate transverse walls. Outside the end walls 40, the vertical wall structure is extended as indicated at 44 to approach 60 closely to the car side walls 51. The vertical wall structure, so formed, is welded along its top and bottom edges to the top and bottom plates to form a rigid, unitary, and substantially integral 65 fan housing structure. Due to such integration,

and due to the fact that the vertical wall structure includes wall units extending both lengthwise and transversely of the housing, the housing structure is very rigid and strong, and capable of rigidly supporting the bulkhead and holding it rigidly in place against load thrusts, and of taking any necessary proportion of its weight. It may be remarked that the housing bottom plate 17, instead of resting on the metallic floor sheathing 18, may be in effect a portion of that sheathing itself. That is, the housing might be formed in place on the floor sheathing as a bottom plate; but for manufacturing convenience, use of a separate bottom plate is preferred.

As so formed, the housing structure presents alternate compartments 45 and 46 which are each open on one side and with their open sides at opposite sides of the fan housing. As here shown the compartments 45 face inwardly toward the ice bunker, under the level of the ice grate, and compartments 46 face outwardly toward the lading compartment under the level of lading floor 11. The several transverse walls 40 and 41, or at least certain of them, are perforated with large central openings 41. A single fan shaft 48, mounted in suitable bearings 49, extends substantially through the complete length of the housing, extending through openings 41 of the several transverse walls. In each of compartments 45 fan shaft carries a radial bladed fan unit 50, bearings 49 being located in the other compartments 46. Rotation of the fan shaft and of the radial bladed fans in either direction draws air from under the lading floor, through compartments 46 which are open to the space under that floor, through openings 41 in the transverse wall structures; and then, thrown outwardly by the fans, the air flows through the open sides of compartments 45 into the space under the ice grate. Suitable openings being provided in the upper part of the bulkhead, rotation of the fans thus sets up a circulation from the space under the lading floor, upwardly through the ice bunker, and outwardly over and downwardly through the load in the lading space.

Although of course the arrangement of the fan housing may be reversed, to make fan compartments 45 face the space under the lading floor and thus draw air downwardly through the ice bunker and force it out into the lading compartment under the lading floor, the reversed direction of circulation above described is preferred for several reasons. It is preferred generally because in most circumstances it sets up a more uniform temperature throughout the load. It is preferred here particularly because that direction of circulation, with the fan located immediately adjacent the ice bunker and with the fan housing structure in full effect forming a part of the ice bunker wall, the melt water, salt or other debris dropping down from the ice grate are driven away from the fan structure and mechanism instead of being drawn into it. To prevent accidental entry of any matter from the bunker into the fan compartments 45, or the entry of any debris from the lading compartment into the housing compartments 46, screens 16a may be extended over the two opposite vertical faces of the housing. These are shown in Fig. 3 but omitted from the other figures for clarity of illustration.

The fan may be driven in any suitable manner and by any suitable mechanism. It may be driven directly by an independent driving motor; and it is designed to be so driven at least when the car is standing. For pre-cooling or similar operations

an electric motor or other primary drive may be applied to the exteriorly projecting hub 54a. Normally, however, it is preferred to drive the fan shaft from the running gear of the car. That drive may take various forms; the following described form is typical.

As here shown, an end bearing 49a for the fan shaft is located at or near one end of fan housing 16, and at that end shaft 48 projects through the side wall structure 51 of the car. Preferably an opening is made through the side wall structure lined with a tubular lining 52, and suitable means in the nature of a packing gland 53 stops off entry of air around the shaft. The outer end of shaft 48 carries a drive pulley 54 which is driven by belt 55 from a driving pulley 56 mounted on the outer end of a drive shaft 57, the inner end of which carries a suitable traction roller 58 adapted to roll in tractive contact with car wheel 59. Drive shaft 57 is mounted in suitable bearings in a tubular support 60 which is carried by two radial arms 61 and 62 which swing around the axis of a supporting shaft 63 mounted in suitable bearings under the floor of the car. Arms 61 and 62 swing about that axis independently of each other and a spring 64 has an end which bears at a suitable intermediate point upon shaft housing 60; so that the spring pressure presses traction roller 58 into contact with wheel 59 and also tends to move pulley 56 downwardly to tension the driving belt 55.

I claim:

1. In a car construction having a car floor, side walls and an end wall, and a lading floor spaced above the car floor and having an end spaced from the car end wall; a combined ice bunker and ventilating structure comprising, a fan housing structure extending in length across the car floor substantially from side to side immediately adjacent the lading floor end, the fan housing being an elongate unitary box-like structure comprising top and bottom plates and an intermediate vertical wall structure comprising staggered longitudinal wall portions and interconnecting transverse wall portions forming a series of compartments alternate ones of which are open at opposite sides of the housing, the housing being spaced from the car end wall with the upper surface of its upper plate flush with the upper surface of the lading floor and forming the lower part of a transverse wall structure which divides an ice bunker compartment adjacent the end wall from a lading compartment whose floor is formed by the lading floor, a fan driving shaft extending lengthwise through the fan housing, certain of the transverse housing walls being perforate, fan units on the shaft in alternate housing compartments, an ice grate in the ice bunker compartment with its upper surface at the level of the lading floor surface, and a bulkhead structure extending across the car interior from side to side, the bulkhead structure being movable between a position against the car end wall and a position over the fan housing where it is supported directly on the housing top plate and forms the upper part of the transverse wall structure which divides the ice bunker from the lading compartment, the housing structure including an upwardly facing channel formation extending longitudinally of the structure at a level below the surface of the top plate, and the lower edge of the bulkhead structure being provided with a downwardly projecting bead adapted to enter the channel formation.
2. In a car construction having a car floor, side

walls and an end wall, and a lading floor spaced above the car floor and having an end spaced from the car end wall; a combined ice bunker and ventilating structure comprising, a fan housing structure extending in length across the car floor substantially from side to side immediately adjacent the lading floor end, the fan housing being an elongate unitary box-like structure comprising top and bottom plates and an intermediate vertical wall structure comprising staggered longitudinal wall portions and interconnecting transverse wall portions forming a series of compartments alternate ones of which are open at opposite sides of the housing, the housing being spaced from the car end wall and forming the lower part of a transverse wall structure which divides an ice bunker compartment adjacent the end wall from a lading compartment whose floor is formed by the lading floor, a fan driving shaft extending lengthwise through the fan housing, certain of the transverse housing walls being perforate, fan units on the shaft in alternate housing compartments, and a bulkhead structure extending across the car interior from side to side, sup-

ported directly on the housing top plate, and forming the upper part of the transverse wall structure which divides the ice bunker from the lading compartment, the thickness of the bulkhead structure being less than the width dimension of the fan housing structure, and the bulkhead being positioned on the housing structure to leave an uncovered portion of the top plate at that edge of the top plate which is adjacent the ice bunker.

3. A combined structure as defined in claim 1, and in which the upwardly facing channel formation is located exteriorly of one of the side walls of the housing structure.
